John Serway, 916 Erie Blvd. W., Rome, N.Y.

Filed Jan. 30, 1964, Ser. No. 78,432

Term of patent 14 years

(Cl. D33—1)

FIGURE 1 is a front elevational view of the door;
FIGURE 2 is a side edge elevational view;

FIGURE 3 is a fragmentary enlarged sectional view taken on the line 3—3 of FIGURE 1;

FIGURE 4 is a fragmentary enlarged sectional view taken on the line 4—4 of FIGURE 1;

FIGURE 5 is a fragmentary enlarged sectional view taken on the line 5—5 of FIGURE 1;

FIGURE 6 is a fragmentary enlarged sectional view taken on the line 6—6 of FIGURE 1, and

FIGURE 7 is a fragmentary enlarged sectional view of one of the four identical corners.

The back of the door is plain and unornamented.

The design is characterized by the combination on the door disclosed of the upper and lower rail members having quarter round outer edges and ogee curved inner edges in association with the rabbeted groove portion, all as shown.

I claim:

The ornamental design for a door for kitchen cabinet, substantially as shown and described.
